EXERCISING APPARATUS

Jere L. Wentz, Passaic, N. J.

Application August 16, 1950, Serial No. 179,816

3 Claims. (Cl. 272—73)

1

This invention relates to exercising apparatus and more particularly to a collapsible and adjustable exercising machine which may be accommodated to the needs and physical condition of the person using it.

An object of the invention is to provide an exercising device which is adaptable for use in different positions and localities whereby different parts of the body may be selectively exercised.

Another object of the invention is to provide an exercising apparatus having a pedal mechanism which is adapted to be positioned for use by a person while either lying in bed or sitting up, as in a chair.

A further object of the invention is to provide an exercising device which is adjustable to different positions so as to be operable at various angles in relation to the position of the person using the machine.

Another object of the invention is to provide an exercising apparatus which has simple means for collectively and individually adjusting the resistance loads against which the person using the machine exercises his limbs and body.

A further object of the invention is to provide an exercising apparatus of simple construction which is collapsible into a single plane for convenient shipping and storage, and which is light in weight.

The features of novelty which I believe to be characteristic of my invention are set forth with particularity in the appended claims. My invention itself, however, both as to its fundamental principles and as to its particular embodiments, will best be understood by reference to the specification and accompanying drawings in which—

Figure 1 is a perspective view of the exercising device as it is operated by a person sitting in a chair with variations of position indicated in dotted outline;

Fig. 2 is a perspective view of a patient using the apparatus while lying in bed, with variations in position indicated in dotted outline;

Fig. 3 is a front view of the exercising apparatus showing the various elements collapsed into a single plane.

Fig. 4 is an enlarged detail, partly in section, taken on line 4—4 of Fig. 3;

Fig. 5 is an enlarged detail, partly in section, taken on line 5—5 of Fig. 3;

Fig. 6 is an enlarged view, partly in section, taken on line 6—6 of Fig. 3, and

Fig. 7 is an enlarged view, partly in section, taken on line 7—7 of Fig. 3.

Referring now to the drawings in detail and

2

particularly to Figs. 1, 2 and 3, the exercising apparatus of the present invention comprises a U-shaped frame 11 having long side arms 12 and 13 extending in the same direction and substantially parallel to each other, and a central connecting portion 16. Rubber or other friction cups 14 and 15 cap the ends of said arms and serve as resilient friction members for purposes to be described. Pivottally connected to the central portion 16 of frame 11 is an inverted T-shaped leg 17 which has a cross-arm or bar 18 which swings between arms 12 and 13. Also attached to the ends of bar 18 are rubber or plastic friction cups 19. Frame 11 and leg 17 are preferably made of a light-weight tubular material, such as aluminum, or the like.

Leg 17 is pivotally connected to frame 11 by means of sleeve 21 encircling said frame and having the free ends of said sleeve attached to the leg 17 by means of bolts 22 (see Fig. 4). In order to maintain the relative positions of leg 17 and frame 11, an annular groove 23 is provided in the portion 16 of the frame, and indentations 24 of sleeve 21 are accommodated in this groove. The groove and indentations cooperate as bearing surfaces, and prevent lateral movement of arm 17 on the central portion 16.

Additional bearing surface is provided by a wooden or other block 25 held captive between sleeve 21, the central frame portion 16 and the end of arm 17, said block being shaped to fit the curvature of frame 11. Block 25 also serves to anchor leg 17 in relation to the frame so as to prevent sidewise angular movement of the leg at that juncture. It is intended that this connection between frame 11 and leg 17 shall be freely pivotal and, if necessary, lubrication may be provided by impregnating block 25 with graphite or the like.

Cross bar 18 may be connected to leg 17 by means of screw bolt 26 extending through bar 18 and engaging bracket 27 secured on the inside of leg 17 by means of bolt 28 (see Fig. 5).

The pedal mechanism of the exercising device comprises a rotatable crank shaft 29 having offset portions 31 extending in opposite directions. Shaft 29 is connected intermediate the ends of leg 17 by means of a pair of blocks 32 and 33 which are secured to the leg and to each other by means of screw bolt 34 and screw knob 35 (see Fig. 7). Recesses 36 and 37 are provided in blocks 32 and 33 respectively, to grasp shaft 29, while knob 35 is intended to be manually adjusted to provide varying amounts of friction resistance against the rotation of said shaft, as desired.

Connected to each extension 31 of shaft 29 are pedal blocks 38 and 39 having recesses 41 and 42, respectively, adapted to grasp extensions 31 (see Fig. 6). Blocks 38 and 39 are held together by means of bolt 43 and wing nut 44. Frictional resistance between blocks 38 and 39 and extension 31 is varied by adjusting wing nut 44. Stirrup straps 45 to be engaged by the feet of the person using the exercising machine may be connected to blocks 39.

In operation, the exercising device of the present invention may be used by a person while sitting in a chair, as shown in Fig. 1. In this position, cross-bar 18 of leg 17 rests upon the floor, and since the ends of cross-bar 18 extend some distance from leg 17, a firm footing is provided for the apparatus, and cups 19 provide sufficient friction resistance to prevent the device from slipping. In this position, the ends 12 and 13 of frame 11 may constitute handles to be grasped in the hands while the feet are engaged by straps 45 of the pedal mechanism. Since leg 17 and frame 11 are pivotable relative to each other, cross-bar 18 can be located to suit the individual or at the distance which provides the best exercise required for particular muscles of the body. Or, the operator may select the distance of the pedals from the body by holding frame 11 tilted forward or backward from the vertical, as shown by the dotted outline in Fig. 1. Or, in another use, while the feet and legs of the person are working the pedal apparatus the person may, at the same time, pull and push frame 11 backward and forward for the purpose of exercising the arms and back muscles while bringing into play different sets of other muscles.

Fig. 2 illustrates another manner in which the exercise apparatus may be used, especially while lying in bed, such as in a non-ambulatory case. In this instance frame 11 is tilted away from the person to form a brace for leg 17 positioned at an angle thereto on either the floor or bed, with the pedal apparatus at the appropriate distance from the person for obtaining the exercise of the proper feet, leg, back and abdominal muscles, as the case may be. Friction cups 14, 15 and 19 serve to provide a firm footing for the frame and cross-arms so that there is no slippage while the apparatus is being operated in this position. Here again, the distance of the pedal mechanism from the person may be adjusted by moving the arms 12 and 13 of frame 11 farther or closer to the position of cross-arm 18, or reversing the position of arms 12 and 13 with respect to leg 17, whereby more or less stretching may be required in the use of the machine, and these different positions bring into play different sets of muscles which may be selectively exercised.

Depending upon the physical condition or requirements of the person, the frictional resistance of the pedal apparatus may be adjusted either where shaft 29 is held by blocks 32 and 33 or at the pedal portions at blocks 38 and 39, or both. Increasing frictional resistance on shaft 29 increases the force required to be exerted by the leg, abdominal and back muscles in rotating the pedals, while increasing the frictional resistance on pedal extensions 31 increases the force required to be exerted by the ankles. Thus,

the exercising machine is adapted not only selectively to exercise different parts of the body but also to vary the force of muscular exertion.

When not in use, the apparatus may be collapsed into one plane as shown in Fig. 3 so that it may be readily packed for shipping and may be stored in a small space; and the apparatus being constructed of few light weight parts may be readily carried from place to place.

In the specification, I have explained the principles of my invention and the best mode in which I have contemplated applying those principles, so as to distinguish my invention from other inventions; and I have particularly pointed out and distinctly claimed the part, improvement or combination which I claim as my invention or discovery.

While I have shown and described certain preferred embodiments of my invention, it will be understood that modifications and changes may be made without departing from the spirit and scope thereof, as will be clear to those skilled in the art.

I claim:

1. An exercising apparatus comprising a frame, said frame having a central portion and two arms extending in the same direction at an angle from said central portion, a leg pivotally connected to said central portion, and being movable between said arms, a cross-bar connected perpendicularly to the free end of said leg, a rotatable crank shaft connected to said leg intermediate the ends thereof, a block connected to said leg and adapted to clamp said shaft, said block being adjustable to vary the frictional resistance applied to said shaft, two extensions on said shaft extending in opposite directions to each other, a pair of blocks on each of said extensions, each said pair of blocks being adapted to clamp an extension between them and to rotate around said extension, and a screw connecting said blocks, said screw being adapted to vary the frictional resistance applied between said blocks and said extensions.

2. Apparatus according to claim 1 further comprising a strap on each set of extension blocks, said straps being adapted to be engaged by the feet of a person whereby said crank shaft may be rotated.

3. An exercising apparatus according to claim 1 further comprising a bearing block positioned at the juncture between said leg and said central portion whereby said leg is anchored firmly in position.

JERE L. WENTZ.
